ATTORNEY.

UNITED STATES PATENT OFFICE.

CHARLES J. E. KELLNER, OF FORT WORTH, TEXAS, ASSIGNOR OF ONE-HALF TO EPHRAIM M. TURNER, OF SAME PLACE.

INSTEP BEARING OR GUARD FOR STIRRUPS.

SPECIFICATION forming part of Letters Patent No. 636,810, dated November 14, 1899.

Application filed November 12, 1898. Serial No. 696,261. (No model.)

To all whom it may concern:

Be it known that I, CHARLES J. E. KELLNER, a citizen of the United States, residing at Fort Worth, Texas, have invented a new and 5 Improved Instep Bearing or Guard for Stirrups, of which the following is a specification.

This invention relates to stirrups and their attachments; and the object is to provide an easy comfortable bearing for the instep of the foot or the shin of the leg which will prevent the foot from rubbing against the supporting-bar or leathers. This stirrup is intended especially for stockmen, who ride with the feet thrust as far as possible forward in the stirrups. It is absolutely necessary to have an easy bearing for the instep of the foot for several reasons. Unless there is an easy rest the instep is chafed by the friction between it and the stirrup-leathers. 15 Something is needed to prevent the wear of the stirrup-leathers by the shoe-eyelets, especially shoe-eyelets which have lip-like hooks for lacing purposes. If there are no eyelets, the leathers wear out the shoes of the rider. 20 It is necessary also to have a brace for the foot, and the instep-guard is made to conform to the shape of the foot. The instep-guard is made of metal and lined with leather, as hereinafter described. 25 Other objects will be better understood from the following description and claims when read in connection with the accompanying drawings, which form a part of this application.

30 Figure 1 is a rear elevation of a stirrup with my improved instep-protector attached. Fig. 2 is a rear elevation of a stirrup, showing a vertical section of the attachment cut through the bearings of the supporting-lugs. 35 Fig. 3 is a side elevation of a stirrup with the attachment in place. Fig. 4 is a plan view of the attachment. Fig. 5 illustrates a variation in the manner of securing the attachment.

40 Similar characters of reference are used to indicate the same parts throughout the several views.

An ordinary stirrup is shown in the drawings, having the sides A and A and the supporting-bar B. It is preferable to mount the at-

tachment or guard D under the supporting-bar B. It is pivotally mounted on the bar d, which passes through two lugs a and b integral with the guard D, and has bearings in the sides of the stirrup. Instead of using a bar d the 55 guard may be pivotally mounted by means of rivets, which would occupy the same position as the ends of the bar occupy in Figs. 1 to 4. If the guard is cast, the lugs a and b may be cast integral therewith, as shown in 60 Fig. 2; but if the guard is formed of metal by stamping or otherwise the lugs may be cut out of the metal forming the guard and bent up to the proper position. The guard may be made of any suitable material; but 65 it is preferable to make it of metal, either of malleable casting or of sheet metal. In form it is double concavo-convex and adapted to conform to the shape of the foot and may be lined, holes c being made therein for lining. 70 The guard stands toward the back of the stirrup or that part of the stirrup next to the foot and is made to stand in this position by pivoting the lugs near the rear edges of the sides of the stirrup and forming the lugs a 75 and b on the back part of the guard, as shown in Fig. 3. When thus mounted, the greater part of the weight of the guard will be in front of the pivotal bearings. Consequently the guard will be forced downward and backward. Instead of pivoting the lugs on a bar 80 d or on rivets, as above explained, the lugs may be long enough to extend up far enough and have two arms m on the upper part for clamping the supporting-bar. Before the 85 arms are bent on the supporting-bar they occupy the position of the dotted lines in Fig. 5. This view, Fig. 5, shows the one of the lugs b' integral with the guard D. When the guard is thus supported, a lug g is made on the lug 90 b' to prevent the guard from swinging too far to the front. In the form of mounting the guard as shown in Fig. 3 the greater weight in front will make the guard stand at the proper place. A portion E of the stirrup- 95 leathers is shown in Fig. 3.

The guard may be made of any practical size, and the shape may be varied to adapt the same to suit the various designs of stirrups on the market.

Having fully described my invention, what I claim as new, and desire to secure by Letters Patent, is—

1. A stirrup having an instep-guard and means for mounting the same below and to the rear of the supporting-bar of the stirrup, said means consisting of lugs formed integral with said guard and projecting upward and a bar passing through said lugs and through the rear edges of the sides of the stirrup.

2. A stirrup having an instep-guard and lugs for pivotally mounting said guard on the side bars of the stirrup below and at the rear of the supporting-bar thereof, the greater portion of the weight of the instep-guard be-

ing located on that side of the lugs which is toward the stirrup whereby the guard is caused to hang at the rear of the stirrup.

3. An instep-guard for stirrups and means for mounting the same, said means consisting of a bar adapted to engage the sides of a stirrup and lugs integral with said guard and engaging said bar.

In testimony whereof I set my hand, in the presence of two witnesses, this 7th day of November, 1898.

CHARLES J. E. KELLNER.
